UNITED STATES PATENT OFFICE.

JOHN L. PAINTER, OF BELLEVUE, OHIO.

TOOL.

SPECIFICATION forming part of Letters Patent No. 415,923, dated November 26, 1889.

Application filed August 13, 1889. Serial No. 320,564. (No model.)

To all whom it may concern:

Be it known that I, JOHN L. PAINTER, of Bellevue, in the county of Huron and State of Ohio, have invented a new and Improved 5 Tool, of which the following is a full, clear, and exact description.

My invention relates to an improved tool, and has for its object to combine in one implement a series of wrenches of different 10 sizes, each capable of independent use, a wire-cutter, pliers, and a screw-driver, the tool being especially adapted for use in connection with self-binding harvesters and other machines in which nuts of various sizes need to 15 be loosened and various parts removed for cleaning; and a further object of the invention is to provide a tool embodying the above features which will be simple in construction and capable of expeditious and convenient 20 manipulation.

The invention consists in the novel construction and combination of the several parts, as will be hereinafter fully set forth, and pointed out in the claims.

Reference is to be had to the accompanying drawings, forming a part of this specification, in which similar letters and figures of reference indicate corresponding parts in all the views.

Figure 1 is a side elevation of the tool. Fig. 2 is an edge view of the same. Fig. 3 is a plan view. Fig. 4 is a section on line *x* *x* of Fig. 1, and Fig. 5 is a section on line *y* *y* of Fig. 1.

The body of the tool comprises two arms 10 and 10, so bent upon themselves and riveted together as to form a pair of pliers A, the surfaces where the arms are riveted being recessed, as shown in Figs. 1 and 2, to produce 35 opposed shoulders 11 and 12, whereby the combined thickness of the tool at the pivotal point where the arms are riveted will be equal to a single thickness of the head, as shown in Fig. 2.

The upper curved portion of the arms forming the jaws 13 and 14 of the pliers is serrated or otherwise roughened upon the inner face to facilitate clamping and turning a pipe or other cylindrical article, and in the edge 45 of each jaw, at the upper end, an angular recess 15 is produced, whereby when the jaws are brought together a rectangular opening

is formed, as shown in Fig. 3, the said recesses greatly facilitating the withdrawal of plunger-bolts, split keys, &c.

55

Below the pivotal point of the arms 10 a blade 16 is secured to each inner edge, as shown in Fig. 1, which blades, when the arms 10 are carried in the direction of one another, contact and serve as wire-cutters, as shown 60 in Fig. 4.

The lower end of one of the arms 10 is made to terminate in a wrench 17 of what is known as the "alligator-jaw" pattern, and the extremity of the other arm is reduced 65 and sharpened to serve as a screw-driver, as illustrated at 18 in Figs. 1 and 2.

Upon the side of the arm 10 having the alligator-jaw wrench attached a series of wrenches 19 are pivoted, graduated in length 70 and each adapted to take a different size of nut. These wrenches 19 rest one upon the other, as shown in Figs. 1 and 2, and are pivoted to the arm of the wrench above referred to by means of a clevis 20, located near the 75 lower end, in which clevis the lower extremities of each of the wrenches are introduced, the clevis being attached to the wrenches and to the arm 10 by means of a bolt or screw 21. Thus it is obvious that any one of the wrenches 80 19 desired may be carried down to the perpendicular position below the lower extremity of the arm to which they are pivoted, as shown in dotted lines in Figs. 1 and 2, and that they are limited in their downward movement by the clevis and held in the perpendicular position or in the plane with the arm 85 to which they are pivoted for convenient use.

Having thus described my invention, I claim as new and desire to secure by Letters Patent— 90

1. As an improved article of manufacture, a tool comprising a pair of pliers having pivoted to one arm or member by a clevis a series of wrenches graduated in length, each capable of taking a different-sized nut, substantially as shown and described. 95

2. As an improved article of manufacture, a tool comprising a pair of pliers having the inner surfaces of the jaws serrated or roughened and the ends of the jaws provided with an angular recess, and a series of wrenches graduated in length, each capable of taking a different-sized nut, said wrenches pivoted to one arm or member of the pliers by means 100

of a clevis and bolt, substantially as shown and described, whereby any one of the wrenches may be carried perpendicularly downward, and is limited in its downward movement, as set forth.

3. As an improved article of manufacture, a tool comprising a pair of pliers having one arm or member terminating in a screw-driver and the other in a wrench of the alligator-jaw pattern, and having the inner surfaces of the jaws roughened or serrated, the upper edge of the said jaws being provided with an

angular recess, a series of wrenches graduated in size, each capable of taking a different-sized nut, pivoted upon the arm of the pliers carrying the wrench at its extremity, and means, substantially as shown and described, for limiting the downward movement of each of the said pivoted wrenches, as and for the purpose specified.

JOHN L. PAINTER.
